UNITED STATES PATENT OFFICE.

LANSING ONDERDONK, OF NEW YORK, N. Y., ASSIGNEE TO UNION SPECIAL MACHINE COMPANY, OF CHICAGO, ILLINOIS, A CORPORATION OF ILLINOIS.

OVERSEAMING-MACHINE.

1,123,574.

Specification of Letters Patent.

Patented Jan. 5, 1915.

Application filed November 9, 1901. Serial No. 81,766.

To all whom it may concern:

Be it known that I, LANSING ONDERDONK, a citizen of the United States, residing at New York, in the county of New York, State of New York, have invented certain new and useful Improvements in Overseaming-Machines, of which the following is a description, reference being had to the accompanying drawing, and to the letters and figures of reference marked thereon.

My invention relates to an improvement in overseaming machines, and particularly to a pull-off and slack take-up for the needle thread, and the object of the invention is to provide a simple and effective device for pulling off thread from the spools to supply the needle at the proper time; and also in the upward movement of the needle to take up the slack in the needle thread caused by the ascent of said needle, thus enabling all the superfluous thread to be taken out and the stitch to be properly drawn up.

In one of its phases, the invention consists in providing a take-up for the needle thread, which is operated independently of the needle bar, it being for convenience attached to the oscillating looper supporting shaft coöperating with stationary eyelets to pull off thread from the spools sufficient for the needle to use up in its downward movement, and to take up the superfluous thread in the upward movement of the needle.

Secondly, the invention consists in providing a take-up for the needle thread, independent of the needle bar or needle operating mechanism, and comprising an oscillating shaft arranged above the cloth plate of the machine, and having a traveling arm coöperating with thread guiding eyelets, which arm pulls off thread from the spools sufficient for the needle to use up in its downward movement, and which takes up this slack as the needle is moving upward.

Finally, the invention consists in the various details of construction and combinations hereinafter referred to in the appended claims.

The invention is illustrated in the accompanying drawings, in which—

Figure 1 represents a front view of so much of a sewing machine as is necessary to a complete understanding of my invention; Fig. 2 is a skeletonized view, showing

the manner of operating the looper and take-up; and Fig. 3 is a plan view of Fig. 2.

In these drawings, the thread-carrying eye-pointed needle 1, is of ordinary construction, and operates in the usual manner 69 from the driving shaft A, through the needle lever B.

C represents a looping hook or spreader supported on double cranks, and operated by a pitman connection D from the needle 65 lever extension D'. This spreader has a hook at its upper end, and reciprocates in the manner shown in the drawings, to catch a loop of needle thread, carrying it to one side, and up above the throat plate into 70 position to be entered by the looper E, as it moves from the rear toward the front of the needle in a curved inclined path.

The looper E is a thread-carrying looper, and its upper end or shank is secured in 75 a collar F clamped to the lower end of the shaft G, which is arranged at an inclination to the cloth plate, and slightly off the vertical, passing through openings in the head of the machine, which form bearings 80 2, 3, for it. At its upper end, the looper supporting shaft is fitted into the socket of a clamping head or block H, provided at its upper end with a ball stud I, over which loosely fits a head K, to which one end of 85 the pitman rod L, is attached. This pitman rod L at its opposite end is screwed into a socket on a head M fitting a ball stud N, carried upon the end of the vertical arm O of the bell crank lever, pivoted at P to the 90 machine standard. The horizontal arm Q of said bell crank lever carries a ball stud, upon which is fitted a head R, upon the upper end of the connecting rod S, which embraces the eccentric T, upon the driving 95 shaft of the machine.

In the rotation of the driving shaft, the inclined shaft which supports the looper is oscillated, carrying the looper from a point in rear of and to one side the needle, around in a curved path inclined to the cloth plate, through the needle loop which has been brought by the spreader or looping hook up into the path of said looper and around in front of the needle, so that 100 the needle in its descent passes through the loop carried on the looper, thus making an overedge stitch.

Adjustably attached to the clamping head or block H, in which the upper end of the 110

looper shaft is secured, is a plate 4, projecting forward toward the front of the machine into a path between a stationary eyelet 5, adjustable on the goose-neck of the machine and another eyelet 6, which is carried by an arm 6^a, that is pivotally secured to a bracket 6^b on the arm of the machine, and said eyelet-supporting arm is at its lower end connected by a link 6^c to the 10 needle bar head or gate 7. The plate 4 has a projecting arm 4^a, at the forward end of which is an eye or opening 8, through which the thread is guided between said two eyelets. From the second eyelet above referred 15 to, the thread is guided to another stationary eyelet 9 on the upper needle bar lug, and from there the thread extends to the eye of the needle in the usual way.

It will thus be seen that I have provided 20 a thread controller comprising spaced thread eyelets between which is arranged an oscillating thread guide which moves from a position adjacent one of said eyelets to a position adjacent to the other thread eyelet 25 and the movements of said thread guide are such that it intersects a line passing through said eyelets at two places which are respectively adjacent said eyelets. It will also be seen that the extreme positions of said 30 thread guide are on one side of the line passing through the eyelets. While this is my preferred arrangement of parts, it will be obvious that said thread guide may be so located relative to the thread eyelets as 35 to move from a position on one side of a line passing through said eyelets to a position on the opposite side of said line. It is essential however, that said thread guide should move from a position closely adjacent 40 cent one of said thread eyelets to a position closely adjacent to the other thread eyelet.

The action of the thread guide upon the thread passing through the thread eyelets is as follows: Assuming that the needle is in 45 its extreme upward position and at this time the spreader carrying the needle loop around the edge of the material is holding the needle loop for the entrance of the looper and the looper has moved forward 50 with its point just entering the needle loop carried by the spreader. The thread guide is moved toward the thread eye 6 and is just engaging the thread for the pulling off action. The movement of the spreader has 55 at this time taken all the slack out of the thread so that as the needle begins its downward movement, the thread is under tension and the movement of the thread guide toward the eyelet 6, operates to pull thread 60 from the supply. The downward movement of the needle together with the forward movement of the looper, holds the thread taut during this movement of the thread 65 guide and therefore, thread is necessarily drawn from the supply. After the point of

the needle enters the looper thread loop, the thread guide begins its movement in the opposite direction and gives up thread to the further movements of the needle. After the needle has passed through the fabric and 70 begins its upward movement, the thread guide is moved into contact with the thread at a point adjacent the thread eyelet 5 and by a further movement of this thread guide, the needle thread will be taken up, for at 75 this time the needle thread is slack. It will thus be seen that the thread guide in its movement from a position adjacent one thread eyelet to the other, operates to pull off sufficient thread from the supply for the 80 formation of the stitch in one of its movements and to take up the slack in the thread in its other movement.

It will be noticed that the needle thread take-up is independent of the needle bar and 85 its operating parts, and while the operation of this pull-off and take-up by the looper supporting shaft is herein claimed as a feature of the invention, it will be understood that the pull-off and take-up may be applied 90 to any suitable oscillating shaft arranged above the bed plate of the machine, and I do not, therefore, wish to be limited, so far as the broad claims of my application are concerned, to any specific details of construction, as various modifications and changes may be made, without departing 95 from the spirit of my invention.

Having thus described my invention, what I claim as new, and desire to secure 100 by Letters Patent, is:—

1. A sewing machine including in combination, a thread-carrying element, a thread controller therefor comprising spaced thread guides, a thread-engaging member 105 engaging the thread between said guides, and means for reciprocating said thread-engaging member from a position at one side of and adjacent one of said guides in a direction away from the same toward the 110 other guide to a position at one side of and adjacent the said other guide, said thread-engaging member operating to pull off thread at one end of its reciprocation, and to take up thread at the other end of its 115 reciprocation.

2. A sewing machine comprising a needle bar, a needle and means for operating it, a thread controller for the needle thread including an oscillating shaft, means for oscillating the same a thread arm carried by said shaft and having a thread eye, stationary thread guides arranged upon opposite sides of said movable arm, said thread eye on the arm moving through an arc which intersects a line passing through the stationary thread guides, whereby said arm moves from a position adjacent one of said thread guides to a position adjacent said other thread guide.

3. A sewing machine comprising a needle bar, a needle and means for operating it; a thread controller for the needle thread including an oscillating shaft, means for oscillating the same, a thread arm carried by said shaft and having a thread eye, stationary thread guides arranged upon opposite sides of said movable arm, said thread eye on the arm moving through an arc which intersects a line passing through the stationary thread guides, whereby said arm moves from a position adjacent one of said thread guides to a position adjacent said other thread guide, the extremities of the path of movement of said thread eye also lying on the same side of the said line passing through the thread guides.
4. A sewing machine comprising a needle bar, a needle and means for operating it, a needle thread pull off and take-up arranged independent of the needle bar and its operating connections and including an oscillating shaft arranged above the cloth plate of the machine provided with an arm moving with it and having a thread eye and stationary thread guides arranged upon opposite sides of said movable arm, said thread eye on the arm moving through an arc which intersects a line connecting the stationary thread guides, the extremities of which are lie upon the same side of said line.
5. A sewing machine pull-off and take-up, comprising an upright vertical shaft mounted in bearings upon the frame of the machine and carrying a projecting thread guiding arm, stationary eyelets mounted upon the machine frame and respectively upon opposite sides of the thread guiding arm, the extent of oscillation of such thread guiding arm being such that at the respective extremities of its movement, it is on the same side of a line passing through the two eyelets and at one extremity of its movement, thread is pulled off from the supply and at the other extremity the slack needle thread is taken up.
6. A sewing machine comprising a needle and means for operating it, a looper, a shaft supporting said looper and mounted in bearings on the machine frame, a thread guiding arm carried by said looper supporting shaft and thread guides upon opposite sides of said thread guiding arm coöperating with the same whereby said thread arm on the forward movement of the looper will pull thread from the supply and on the backward movement of the looper will take up the slack in the needle thread.
7. A sewing machine comprising a needle, means for operating it, an oscillating shaft arranged above the cloth plate of the machine, a looper supported on said oscillating shaft, a spreader arranged to take a loop of thread beneath the work plate and carry it above the same to be engaged by the looper, a thread guiding arm carried by said shaft, thread guides arranged on opposite sides of said thread guiding arm and coöperating therewith, whereby said thread arm on the forward movement of said looper will pull thread from the supply and on the backward movement of said looper, will take up the slack in the looper thread.
8. In an overseaming sewing machine, a needle and means for operating it, an oscillating shaft, a looper supported thereon and coöperating with the needle above the work support, a spreader arranged to take a loop of needle thread beneath the work plate and carry it above the same to be engaged by the looper and a needle thread pull-off and take-up including a thread guiding arm carried by and oscillating with the looper supporting shaft and coöperating thread guides upon opposite sides of said thread guiding arms, the extent of oscillation of said thread guiding arm being such that at one extreme of its movement, it moves to a point adjacent one of said thread guides and pulls thread from the supply and at the other extremity of its movement said thread guiding arm moves to a position adjacent the other thread guide and takes up slack in the needle thread.
9. In a sewing machine having suitable stitch forming mechanism, a pull-off and take-up therefor, comprising two stationary eyelets and a thread arm engaging the thread between said eyelets and swinging in the arc of a circle from a position adjacent one of said eyelets, to a position adjacent the other eyelet and at the extremities of its movement, lying on the side of the line connecting the stationary eyelets whereby said thread arm at one end of its stroke pulls thread from the supply and at the other end of its stroke, takes up the thread.
10. In a sewing machine comprising a needle and an oscillating looper, a shaft supporting said looper, a rigid arm fixed to said shaft and having a thread eye, and co-operating thread guides arranged upon the opposite sides of said thread eye, means for moving said shaft whereby said thread eye moves from a position adjacent one of said thread guides to a position adjacent said other thread guide.
11. A sewing machine having suitable stitch forming mechanism, a pull-off and take-up therefor, comprising a thread guiding arm mounted upon an upright axis, two stationary eyelets with means for swinging the guiding arm on its axis, said guiding arm at the extremities of its movement lying on the same side of a line connecting said stationary eyelet.
12. A sewing machine having suitable stitch forming mechanism, a pull-off and take-up therefor, comprising a thread guiding arm mounted upon an upright axis, two

stationary eyelets, means whereby one of said eyelets may be adjusted and means for swinging the thread guiding arm on its axis, said guiding arm at the extremities of its movements lying on the same side of a line connecting said stationary eyelets.

13. A sewing machine having suitable stitch forming mechanism, a pull-off and take-up comprising a thread guiding arm 10 swinging in the arc of a circle and two sta-

tionary eyelets, the guiding arm at the extremities of its movement lying outside a line connecting the stationary eyelets and means for adjusting the thread guiding arm.

In testimony whereof I affix my signature 15
in presence of two witnesses.
